UNITED STATES PATENT OFFICE.

WALTER G. E. BOLAFF, OF ST. LOUIS, MISSOURI.

COMPRESSOR.

Application filed August 7, 1925. Serial No. 48,725.

This invention relates to improvements in rotary compressors, designed more particularly for use in the art of mechanical refrigeration, but, in principle, equally applicable 5 for use in the general art of displacing liquids and gases.

Certain broad principles of the invention are described and claimed in my prior applications Serial Nos. 33,951 and 33,952, filed 10 June 1st, 1925, the first showing the embodiment of the invention in a rotary pump in which the rotor engages directly with the end walls of the cylinder, and the second showing the invention embodied in a rotary 15 compressor in which the rotor is provided with a unitary head, preferably formed integral therewith, the end of the rotor and the inner wall of the head engaging opposite ends of the cylinder, respectively, to 20 form sealing contact therewith.

The object of the present invention is to provide a floating head in place of the unitary head shown in my application Serial 25 No. 33,952, above referred to, and to provide means for actuating this floating head at a definite speed from the shaft which actuates the rotor. In the preferred embodiment of the invention, as shown in the drawings, this is accomplished by an eccentric 30 mounted on the shaft, on which the rotating head has a sliding fit. The invention contemplates the use of two floating heads instead of a single floating head at one end of the rotor, and it is within the scope of 35 the invention to give the floating head, or the floating heads if two be employed, a sliding fit on the shaft of the rotor, and to hold the head or the heads to the end or ends of the cylinder by developed pressure, without employing an eccentric connection 40 between the shaft and the floating head or heads.

The invention is illustrated in the accompanying drawings, in which—

45 Figure 1 is a view partly in longitudinal section and partly in elevation showing one embodiment of the invention, in which a single floating head slidably mounted on the operating shaft is employed;

50 Figure 2 is a similar view showing the use of two floating heads; and

Figure 3 is a view partly in cross-section and partly in elevation of either of the machines shown in Figures 1 or 2.

55 Referring now to the drawings, the numeral 1 (Figure 1) indicates a casing com-

prising end sections 2 and 3 bolted to a central annular section 4, the inner surface 5 of which constitutes the working surface of a cylinder having a working chamber 6. 60 The inner face 7 of the end section 2 of the casing forms one wall of this cylinder, and the other wall is formed by a floating head 8 which bears against and forms sealing contact with one end of a hollow rotor 9, the other end of which bears against the flat face 7 of the end section 2 to form a sealing contact therewith for the chamber 6. The inner side of the head 8, beyond the rotor 9, bears against an annular flange 10 on the 65 annular section 4 to form a sealing contact at this end of the cylinder for the chamber 6. Each of the sections 2 and 3 is recessed, as indicated at 11 and 12, respectively, to provide space for anti-friction bearings 13 and 14, in which bearings is mounted a drive 70 shaft 15. This drive shaft, in the preferred embodiment of the invention, is provided with an eccentric 16 on which the sliding head 8 is centrally and rotatably mounted. 75 As the shaft rotates, the eccentric 16 imparts an eccentric movement to the head 8, so that the latter is actuated at a definite speed, and its inner face is caused to continuously wipe over the face of the annular flange 10, which insures a smooth clean bearing 80 between the two surfaces to preserve the air-tight contact between them in the operation of the compressor. Sealing contact between the floating head, the flange 10 and one end of the rotor 9 (that at the right 85 shown in Figure 1), and between the other end of the rotor and the wall 7 of the cylinder, is maintained by developed pressure in the operation of the machine. The annular rotor 9 is mounted on the shaft 15 in such manner as to provide for automatically producing and maintaining a sealing contact 90 with the wall 5 of the cylinder, and also to be self-aligning therewith.

100 To this end, I provide on the shaft 15 a second eccentric 17 which is circular in cross-section, and mount on this eccentric an eccentric sleeve 18. That is to say, the sleeve 18 has an eccentric bore which fits on the eccentric 17 so as to be capable of rotating thereon, the construction providing a double eccentric, which functions automatically as a take-up for the space between the rotor and the cylinder. Mounted on the eccentric 105 sleeve 18 to extend between the same and the inner wall of rotor 9 is a single self-aligning 110

bearing 19 which supports the rotor. This bearing, in combination with the eccentric sleeve 18, allows universal alinement of the rotor to the cylinder wall, both as to parallelism and plane. The stuffing box for the end of the shaft which projects through the wall of the cylinder is in the form of a metal bellows 20, the outer end of which is screwed on the shaft 15, as indicated at 21, and the other end of which bears against an inner wall 22, constituting the outer wall of the bearing recess 12, which wall is provided with a shaft opening 23 of larger diameter than the shaft, through which the medium being compressed can pass into the bellows 20, which will, accordingly expand and force its other end, which is in the form of a packing ring 24, firmly against the outer side of the wall 22 to make sealing contact therewith and prevent the escape of the compressed medium. The bellows 20 is located in a chamber 25 cast in the casing section 3, which chamber is closed by a plate 26, operated to permit the driving end of the shaft to pass through it.

In the modification shown in Figure 2, instead of having one end of the rotor engage the wall of the cylinder, as just described, I employ a second floating head, indicated at 27, which is mounted upon an eccentric 28 in the same manner as the head 8 is mounted on the eccentric 16. The end section of the cylinder corresponding to the end section 2 of Figure 1, is indicated by the numeral 29 and, as shown, is provided with an annular space or chamber 30 for containing lubricant under pressure, as will hereinafter appear.

Referring now to Figure 3, the numeral 31 indicates an inlet or suction port, through which the medium to be compressed may pass or be sucked in in the operation of the compressor. To this port is connected a pipe 31^a leading from the low side or expansion chamber of the refrigerating system, and through which the refrigerant is returned for compression, as will be understood. The numeral 32 indicates an outlet from the cylinder, which is provided with any suitable form of chuck valve 33. The ports 31 and 32 are preferably provided in a casting formed integral with the cylinder, and intermediate these ports, a portion 34 of this casting is provided with a slot 35, which is of the length of the cylinder 6, and in this slot is located a blade 36 which is preferably of the self-packing type of my prior Patent No. 1,280,306, dated October 1st, 1918. This blade may be briefly described as comprising a back-plate 37, having at its outer end a shoulder 38 extending throughout the length and of the width of the slot, on which back-plate are mounted two tapered packing packing plates 39 and 40 (Figures 1 and 2), and in the wedge-shaped space between these

packing plates, a freely-movable wedge-plate 41. This blade may be held in sealing contact with the surface of the rotor 9 by any suitable elastic means, such as a spring or fluid, as shown and described in my prior application Serial No. 33,951, above referred to; but I prefer to use a fluid, and, specifically, utilize the lubricant employed in the system for this purpose.

To this end, the outer end of the slot 35 terminates in a small chamber 42 with which communicates one end of a pipe 43, which is screwed into the annular section 4, the other end of said pipe being screwed into the wall of the casing section 3 near the bottom thereof to communicate with an annular chamber 46, which surrounds a central inwardly-projecting cylindrical casting 45, in which is housed the bearing 14 and bellows 20, previously described. This casing is an integral part of the casing section 3. According to this construction, when the rotor is placed in operation, the medium being compressed passes through the pipe 43 into the chamber 42 and forces the inner edge of the blade 37 into sealing contact with the surface of the rotor, and, of course, maintains such contact.

In order to facilitate the direct pressure of the fluid upon the central wedge-plate 41, an opening 44 may be provided in the shoulder 38 to permit access of the fluid to the wedge-plate, which, accordingly, operates to force the packing plates 39 and 40 into engagement with the end walls of the cylinder to form sealing contact therewith, which contact is automatically maintained during the operation of the compressor.

The bearing 14 and the bellows 20 are housed within the casting 45. The chambers 30 and 46 are supplied with a suitable lubricant, such as oil or glycerine, the level of which in the chambers is maintained at about the height indicated by the dotted line 47. Mounted on top of the casing section 3 is an oil-separating chamber 48, which communicates with the chamber 46 by means of a pipe 49. Leading from the upper end of this chamber is a pipe 50 which, when the compressor is combined with a refrigerating system, conducts the compressed gaseous refrigerant from the chamber 48 to the ordinary condenser. Connected with the outlet port 32 is a pipe 51 (Figure 3) which conducts the compressed gas and oil from the compressor to the oil-separating chamber 48. In this chamber, the oil separates from the refrigerant and flows back into the chamber 46, while the gaseous refrigerant passes out through pipe 50 to the condenser, as stated. From the condenser, the refrigerant would pass to the expansion coils or chamber of a refrigerating system and thence be drawn back into the compressor through the pipe 31.

In the operation of the device, as the shaft 15 rotates, the combined operation of the double eccentric 17 and 18 causes the rotor 9 to gyrate, or roll over the surface of the wall of the cylinder chamber 6. In this operation, the medium to be compressed, which in connection with the art of refrigeration, would be a suitable gas, such as methyl chloride, will be drawn in through port 31, compressed in the chamber 6, and forced out through port 32. A certain amount of lubricant in the chamber 46 will pass out with the gas, and gas and lubricant will be forced through pipe 51 into chamber 48 in the manner previously stated. The lubricant in the chamber 46 will be under pressure, as chamber 46 communicates with chamber 48 into which the compressed gas is delivered, which causes the lubricant to be forced through pipe 43 into the small chamber 42 above the blade 37, upon which it exerts its pressure, and forces the lower edge of the blade into sealing contact with the surface of the rotor 9. Ordinarily, the oil can leak past the shoulder 38 to exert its pressure upon the wedge-plate 41, but the provision of the small aperture 44 in the shoulder will be found desirable in the interest of permitting the pressure of the oil to be exerted directly upon the wedge-plate. In either event, the packing plates 34 and 35 will be forced into sealing contact with the end wall 7 of the cylinder and with the inner face of the floating head 8 of Figure 1 or with the inner faces of the floating heads 8 and 27 of Figure 2.

As in the case of the device of my prior application Serial No. 33,952, suitable springs 52 may be located in the chamber 46 to exert pressure upon the floating head 8, so that the operation of compression may start simultaneously with the rotation of the shaft 15. Similar springs 53 may be employed in the chambers 30 and 46 of the device of Figure 2 to act on the floating heads 8 and 27 for the same purpose. It is not absolutely essential, however, that any means should be employed for forcing these floating heads into sealing contact with the wall of the cylinder, as, after a few moments of operation, sufficient pressure will be developed on the oil in the chamber 46, or in the chambers 30 and 46, to cause the latter to force the heads into sealing contact with the cylinder.

The action of the double eccentric, comprising the shaft eccentric 17 and eccentric sleeve 18, has been fully set forth in my prior application Serial No. 33,951, referred to, and it need only be said here, in the interest of a complete understanding of the invention, that these eccentrics operate through the medium of the self-aligning bearing 19 to force the rotor outward into engagement with the wall of the chamber

6, and to maintain a constant automatic adjustment of the rotor to compensate for wear. Furthermore, the contact pressure of the rotor with the wall of the cylinder will be in direct proportion to the resistance offered to the movement of the rotor by the degree of pressure within the chamber 6, due to the resistance offered by the medium being compressed. This is due to the fact that with increased resistance to the movement of the rotor, the latter is automatically forced into firmer contact with the wall of the cylinder by the action of the eccentrics. Sealing contact of the rotor with the wall of the cylinder is therefore always maintained.

A highly important feature of the invention is the fact that, in the device of Figure 1, I employ a floating head 8 which is independent of the rotor, which may move away from the flange 10 of the cylinder to permit the escape of compressed gas from the chamber 6 under a condition of excessive pressure in said chamber, and which is positively actuated by the eccentric 16 on the shaft to have imparted to it a corresponding eccentric movement, so that its inner surface and the surface of the flange 10 and of the ends of the rotor engaged by it will be maintained bright and clean in the area of contact, thus preventing any tendency to leakage. Furthermore, the wear caused by the frictional engagement of the head with the ends of the cylinder and of the rotor will be uniform and over a defined area, so that no unevenness between the engaging surfaces can well develop, and sealing contact between such surfaces will be maintained under conditions of wear during the life of the machine. The ability of the floating head to move away from the flange 10 to permit the escape of gas is, of course, due to the fact that it is not fixed to the rotor or to the shaft, but is slidably mounted on the eccentric 16, which, as shown, is slightly wider than the floating head, so that said head is free to move longitudinally.

What is said above as to the floating head 8 of Figure 1 is, of course, equally applicable to the floating heads 8 and 27 of Figure 2.

I have shown no definite passage connecting the chamber 46 with the chamber 30 to permit the passage of oil from one to the other as, under the very high pressure developed in the operation of the machine, the oil would readily pass through the bearings from one chamber to the other.

The provision of a floating head, or floating heads, capable of longitudinal movement is of very great advantage, as it provides for the release of pressure within the chamber 6 in the simplest possible way, avoids the use of check valves and the like, and hence

permits of the employment of the minimum number of parts for the compressor. The same advantage, of course, pertains to the construction shown in my prior application 5 Serial No. 33,952, but in the present case, the floating heads, in addition, are adapted to be moved at a definite speed over the surface of the end wall of the cylinder, as above described.

10 As in the case of the compressor of my prior application above referred to, the present invention may be used as the prime mover by making such modifications of application as are within the knowledge of those 15 skilled in this art.

I claim:

1. A machine of the class described, comprising a cylinder closed at one end, a rotor mounted for gyratory movement within the cylinder in co-operative relation with the wall thereof, a floating head releasably engaging one end of said rotor and the other end of said cylinder to close the latter, and means for holding said head in fluid-tight 25 contact with the end of the rotor and said other end of the cylinder.

2. A machine of the class described, comprising a cylinder closed at one end, a rotor mounted for gyratory movement within the cylinder in co-operative relation with the wall thereof, a floating head releasably engaging one end of said rotor and the other end of said cylinder to close the latter, means for continuously moving said head in 30 the operation of the compressor, and means for holding said head in fluid-tight contact with the end of the rotor and said other end of the cylinder.

3. A machine of the class described, comprising a cylinder closed at one end, a rotor mounted for gyratory movement within the cylinder in co-operative relation with the wall thereof, a floating head releasably engaging one end of said rotor and the other 40 end of said cylinder to close the latter, means for continuously imparting a gyratory movement to said head in the operation of the compressor, and means for holding said head in fluid-tight contact with the end of the rotor and said other end of the cylinder.

4. A machine of the class described, comprising a cylinder closed at one end, a rotor mounted for gyratory movement within the cylinder in co-operative relation with the 45 wall thereof, a rotary shaft for actuating said rotor, an eccentric on said shaft, a floating head slidably mounted on said eccentric and engaging one end of said rotor and the other end of said cylinder to close the latter, and means for holding said head in fluid-tight contact with the end of the rotor and said other end of the cylinder.

5. A machine of the class described, comprising a stationary cylinder closed at one 50 end, a rotor mounted for gyratory movement

within the cylinder in co-operative relation with the wall thereof, a floating head releasably engaging one end of said rotor and the other end of said cylinder to close the latter, and means for holding said head in fluid-tight contact with the end of the rotor and said other end of the cylinder. 70

6. A machine of the class described, comprising a cylinder closed at one end, a rotor mounted for gyratory movement within the cylinder in co-operative relation with the wall thereof, and a floating head releasably engaging one end of said rotor and the other end of said cylinder to close the latter and adapted to be held in fluid-tight contact with the end of the rotor and the said other end of the cylinder by the developed pressure of the compressor. 75

7. A machine of the class described, comprising a stationary cylinder closed at one end, a drive shaft mounted therein, an eccentric mounted on said shaft, a rotor rotatably mounted on said eccentric, a floating head releasably engaging one end of said rotor and the other end of said cylinder to close the latter and slidably and eccentrically mounted on said drive shaft, and means for maintaining said floating head in fluid-tight contact with the end of the rotor and said other end of the cylinder. 85

8. A machine of the class described, comprising a stationary cylinder closed at one end, a drive shaft mounted therein, a double compensating eccentric mounted on said shaft, a rotor rotatably mounted on said double eccentric in co-operative relation with the wall of said cylinder, a floating head engaging one end of said rotor and the other end of said cylinder to close the latter and slidably and eccentrically mounted on said shaft, and means for holding said head in fluid-tight contact with the end of the rotor and said other end of the cylinder. 95

9. A machine of the class described, comprising a cylinder, a rotor mounted for gyratory movement within the cylinder in co-operative relation with the wall thereof, said rotor having an end releasably engaging one end of the cylinder, a floating head releasably engaging the other end of said rotor and the other end of said cylinder to close the latter, and means for holding said head in fluid-tight contact with said other ends of the rotor and cylinder. 105

10. A machine of the class described, comprising a stationary cylinder, a drive shaft mounted therein, an eccentric mounted on said shaft, a rotor slidably and rotatably mounted on said eccentric and having an end releasably engaging one end of said cylinder, a floating head releasably engaging the other end of said rotor and the other end of said cylinder to close the latter, said head being subject to pressure developed within the compressor, whereby it will be maintained 110

in fluid-tight contact with the ends of the rotor and cylinder which it engages, and said rotor will be maintained at its other end in fluid-tight contact with the cylinder.

- 5 11. A machine of the class described, comprising a stationary cylinder, a drive shaft mounted therein, an eccentric mounted on said shaft, a rotor slidably and rotatably mounted on said eccentric and having an end 35
10 releasably engaging one end of said cylinder, a floating head releasably engaging the other end of said rotor and the other end of said cylinder to close the latter and being slidably and eccentrically mounted on said shaft, 40
15 said head being subject to pressure developed within the compressor, whereby it will be maintained in fluid-tight contact with the ends of the rotor and cylinder which it engages, and said rotor will be maintained at 45
20 its other end in fluid-tight contact with the cylinder.
12. A machine of the class described, comprising a casing providing a chamber for receiving a lubricant, a cylinder mounted in 50
25 said casing and having one of its ends suitably closed, a rotor mounted for gyratory movement within the cylinder in co-operative relation with the wall thereof, a floating head releasably engaging the other end of 55
30 said cylinder to close the same and exposed

to the lubricant within said chamber, and a separating chamber adapted to receive the compressed medium and lubricant from the cylinder and communicating with the chamber of said casing, whereby said floating head 35
will be maintained in contact with said other end of the cylinder by pressure developed within the machine.

13. A machine of the class described, comprising a casing providing a chamber for receiving a lubricant, a stationary cylinder mounted in said casing and having one of its ends suitably closed, a rotor mounted for gyratory movement within the cylinder in co-operative relation with the wall thereof, 45
a floating head releasably engaging one end of said rotor and the other end of said cylinder to close the latter and exposed to the lubricant within said chamber, and a separating chamber adapted to receive the compressed medium and lubricant from the cylinder and communicating with the chamber of said casing, whereby said floating head will be maintained in fluid-tight contact with the end of the rotor and said other end of 55
the cylinder.

In testimony whereof, I have hereunto set my hand.

WALTER G. E. ROLAFF.
